UNITED STATES PATENT OFFICE.

PIO MARFORI, OF FERRARA, ITALY, AND OSWALD SCHNIEDEBERG, OF STRASBURG, ALSACE, ASSIGNORS TO C. F. BOEHRINGER & SOEHNE, OF WALDHOE, NEAR MANNHEIM, GERMANY.

IRON-ALBUMEN PREPARATION AND MODE OF MAKING SAME.

SPECIFICATION forming part of Letters Patent No. 505,986, dated October 3, 1893.

Application filed April 13, 1893. Serial No. 470,247. (Specimens.)

To all whom it may concern:

Be it known that we, PIO MARFORI, a citizen of the Kingdom of Italy, residing at Ferrara, Kingdom of Italy, and OSWALD SCHNIEDEBERG, a citizen of the German Empire, and residing at Strasburg, Alsace, German Empire, have invented certain new and useful Improvements in Iron Derivatives of Albumen and the Method of Preparing the Same; and we do hereby declare the following to be a full, clear, and exact description of the invention, such as will enable others skilled in the art to which it appertains to make and use the same.

This invention relates to the artificial production of iron derivatives of albumen essentially differing in constitution from the heretofore known albuminates of iron or iron salts of albuminous acids.

The object of the said invention is to produce iron compounds of the same character and capable of ready assimilation in the same proportion as certain iron derivatives of albumen existing in food and in the animal organism. These compounds may be used, first, as medicinal compounds which may be prescribed for the usual therapeutic purposes and administered in doses which are readily determined and which vary according to the amount of iron which it is desired to introduce into the system; and secondly, as an article of food for children and other anæmic persons, in which capacity it may be used either alone or as an addition to food, *e. g.*, milk.

Our invention for this purpose consists in the methods, steps and features and the article to be hereinafter described and pointed out in the claims.

When albuminous substances, such as egg-albumen, serum-albumen, fibrin, muscle-albumen, &c., are heated with alkalies there are produced so-called alkaline albuminates. Similar salts are produced with calcium and iron, &c. The present invention, however, is designed to produce iron-derivatives of albuminous acid which widely differ and are sharply distinguished from the iron salts of albuminous acid, by very radical character-

istics and properties. The preferred method of preparing these novel derivatives will now be described, but it should be borne in mind that the same may be greatly varied in many particulars without departing from the gist and essence of our invention.

Under the preferred form of carrying out our invention, we take one hundred parts of an albumen, such as egg-albumen, and dissolve the same in two thousand parts of cold distilled water by shaking. This solution is treated successively with, first, twenty-five parts of ferrous or ferric tartrate dissolved in two hundred and fifty parts of distilled water and neutralized with a ten per cent. soda-lye; second, one hundred parts of a ten per cent. neutral solution of tartrate of sodium; third, thirty eight parts of a ten per cent. soda lye. The resultant solution is warmed to 90° centigrade until a perfectly clear thin brownish red solution is attained, that is to say, until the deep or black-red color which occurs after about one to two hours, has changed to a somewhat lighter red. This generally occurs after from two and a half to four hours. In order to remove the great surplus of alkali, the solution, after cooling, is treated with a twenty-five per cent. solution of tartaric acid, until acid reaction occurs and the excess of acid is then removed by adding a twenty-five per cent. solution of ammonia and continuing such addition until a distinct alkaline reaction takes place. The alkaline solution is then kept at a temperature of 90° centigrade, for not less than twelve, and, preferably for forty-eight hours, whereupon the same is allowed to cool and is then treated with a twenty-five per cent. solution of tartaric acid until the same reacts distinctly acid, whereby the iron derivative of albumen is precipitated as a voluminous precipitate in color and form similar to freshly precipitated ferric or ferrous hydrate and in this way separated from all other noxious and undesirable salts and constituents. The precipitate is then put in the filter and washed until no more iron can be detected in the filtrate.

To further purify the precipitate or moist

mass obtained the same is dissolved in fourteen hundred parts of distilled water, to which twenty parts of a twenty-five per cent. ammonia solution and twenty parts of a ten per cent. neutral, or rather weakly alkaline solution of tartrate of ammonium are added and then heated to 90° centigrade, for not less than twelve and preferably forty-eight hours. The mixture is then thoroughly cooled and 5 treated with a twenty-five per cent. solution of tartaric acid, until a distinct acid reaction takes place, when the precipitate formed is filtered and washed in the filter with distilled water, until the acid reaction disappears. The 10 resultant moist mass is then dried at a slightly raised temperature, thus forming an amorphous dark or light-brown colored powder or thin scales of dark or light-brown color.

The above constitutes what we consider 15 the best way of carrying our invention into effect. But the method thus detailed may be variously and widely modified without departing from our invention. Thus, for example, in place of the soda salt of tartaric acid, 20 other alkali salts of tartaric and other acids may be used, provided they are capable of keeping the iron in solution in the presence of alkaline solutions of lyes. And it is even possible to dispense with such alkali salts in 25 cases where the albuminous substances are themselves capable of retaining the iron salts in solution in the presence of an alkali, such as soda-lye, &c. It should be observed, moreover, that other acids may be used in lieu of 30 the tartaric acid, and other iron salts may be used in lieu of those above set forth.

Other alkaline solutions of lyes than those set forth may also be used with advantage. The temperature and proportions may also be 35 modified within certain limits. The temperature especially may be considerably less than 90° centigrade, and the compound may be formed even at ordinary temperature, in which case, however, its formation is very 40 considerably delayed, the rule being that time consumed in such formation increases as the temperature is diminished or lowered.

In general it should be distinctly understood, that the most essential feature of our 45 process consists in keeping continuously for a long period—which should in no case be less than twelve hours—an albuminous substance in the presence of an iron salt, an alkali and, preferably, though not necessarily, an alkali salt. The iron derivative of albumen so obtained is of a dark or light-brown color, insoluble in water and slightly acidified water, but soluble in a great surplus of tartaric acid. On the other hand, the same is readily soluble 50 in weakly alkaline cold water directly after precipitation. When dried it is readily soluble in weakly alkaline warm water. It contains about from seven to ten per cent. iron, but not in the form of an iron salt. It is an 55 amorphous powder and may be also prepared

in thin scales. When heated over 50° centigrade, it decomposes. In a neutral solution it does not coagulate by boiling.

The iron derivatives of albumen formed at the beginning of the reactions in our process 60 is subsequently so transposed by the long continued heating to 90° centigrade in the presence of an alkali, such as soda-lye (and, preferably, an alkali-salt such as the tartrate of soda), that the molecule of the albumen is 65 changed and the iron forms a part of such molecule and is there bound so intimately that it cannot be separated by the ordinary reagents.

Only by a complete decomposition of the 70 compound can the iron be brought in a form in which it can be detected. It is due to this fact that the iron of this preparation, which is capable of certain and ready assimilation when introduced into the animal and human 75 system, cannot be withdrawn by the sulphurated hydrogen present in the intestines and cannot be modified to such an extent, as is the case with other preparations of iron, whose iron is at once precipitated as sulfid of iron 80 by the hydrogen sulfid. On the other hand, the iron in the present compound as a derivative of albumen is not so intimately bound in the molecule as in the ferro- and ferri-cyanides which are without value as therapeutic 85 and nutritive iron-compounds, and hence, are never used for such purposes.

In order to define the present compound with still greater accuracy, the following reaction or test, which serves to sharply identify the same, is given: Twenty cubic centimeters of an ammoniacal solution containing 0.06 grams of the iron derivative of albumen formed by our process are not modified within five minutes after a drop of a fifty per 90 cent. aqueous solution of sulphid of ammonium (Fresenius: *Qualitative Analysye* fourteenth edition, page 68) has been added, and after twenty-five minutes the same does not attain an opaque black color, after such addition.

As already stated the importance of this invention is mainly due to the fact that the product is essentially similar to iron compounds formed by the animal organism itself, 105 and capable of being readily assimilated in the mentioned proportion therein, and that it may hence be easily and conveniently administered in such doses as will result in a sufficient supply to and reception in the system of the required iron. These facts have been demonstrated by extensive and exhaustive experiments. Not less important is its use as a food-compound which may be used alone, inasmuch as it essentially consists 110 solely of albumen and iron, or as an addition to articles of food, as, for example, milk. The milk which is given to infants and other anemic persons is considerably increased in 115 value and improved in its nutritive proper- 120

130
135

ties by this addition, and in this form may serve as the principal and even exclusive article of diet. We consider this last property which has been demonstrated beyond a per-
5 adventure as one of the greatest advantages resulting from our invention.

Our new food compound or medicine may be used in the dried solid state or in solution.

10 What we claim, and desire to secure by Letters Patent, is—

1. The process of obtaining an iron com-
15 pound capable of resorption in the animal
organism, which consists in keeping an al-
buminous substance in solution in the pres-
ence of an iron salt and an alkali, substan-
tially as set forth.

2. The process of obtaining an iron com-
20 pound capable of resorption in the mentioned
proportion in the animal organism, which
consists in heating albuminous substances in
the presence of an iron salt and an alkali,
substantially as set forth.

25 3. The process of obtaining an iron com-
pound capable of resorption in the animal
organism, which consists in adding albumi-
nous substances to an iron salt in the presence
30 of an alkali and heating the mixture for a
period of not less than twelve hours, substan-
tially as set forth.

35 4. The process of obtaining an iron com-
pound capable of resorption in the mentioned
proportion in the animal organism, which
consists in heating an albuminous substance
40 in solution in the presence of an iron salt and
an alkali for a period of about two and a half
to four hours, then treating the same with an
acid to remove the alkali, then again render-
ing the same alkaline and finally heating for
45 a period not less than twelve hours, substan-
tially as set forth.

50 5. The process of obtaining an iron com-
pound capable of resorption in the mentioned
proportion in the animal organism, which
45 consists in adding to a solution of albumen,
a solution of an iron salt, a neutral solution
of an alkali-salt and an alkaline solution,
then heating for a period of about two and a
55 half to four hours, then removing the sur-
plus of alkali by an acid, then again render-
ing the solution alkaline and finally heating
the alkaline solution for a long period of not
less than twelve hours, substantially as set
forth.

55 6. The process of obtaining an iron com-
pound capable of resorption in the mentioned
proportion in the animal organism, which
60 consists in adding successively to a solution
of an albumen, a solution of an iron salt, a
neutral solution of tartrate of sodium, and
soda-lye, then warming the resultant liquid
for about two and one half to four hours, then
65 adding an acid solution to remove the sur-
plus of alkali, then again rendering the solu-
tion alkaline and then keeping the solution
at a temperature of about 90° centigrade, for

not less than twelve hours, substantially as
set forth.

7. The process of obtaining an iron com-
70 pound capable of resorption in the mentioned
proportion in the animal organism, which
consists in keeping albuminous substances in
solution in the presence of an iron salt and
an alkali, and then precipitating the result-
75 ing iron derivative of albumen by an acid so-
lution for removing noxious and undesirable
salts and other constituents, substantially as
set forth.

8. The process of obtaining an iron com-
80 pound capable of resorption in the mentioned
proportion in the animal organism, which
consists in heating albuminous substances in
the presence of an iron salt and an alkali, and
then precipitating the resulting iron deriva-
85 tive of albumen by a solution of tartaric acid,
substantially as set forth.

9. The process of obtaining an iron com-
90 pound capable of resorption in the mentioned
proportion in the animal organism, which
consists in adding successively to a solution
of an albumen, a solution of tartrate of iron,
a neutral solution of tartrate of sodium and
95 a soda-lye, then warming the resultant solu-
tion to 90°, centigrade, for from two and a
half to four hours, then adding a solution of
tartaric acid to remove the surplus of alkali
and then adding ammonia solution to render
100 the liquid alkaline and finally keeping the
mixture at a temperature of 90°, centigrade,
for a period of not less than twelve hours,
substantially as set forth.

10. The process of obtaining an iron com-
105 pound capable of resorption in the mentioned
proportion in the animal organism, which
consists in heating albuminous substances in
solution in the presence of an iron salt and
alkali, and then precipitating the resulting
110 iron derivative of albumen by an acid solu-
tion, then purifying the precipitate by filter-
ing and dissolving in distilled water mixed
with a solution of ammonia and a solution of
tartrate of ammonia and then keeping the
115 solution at 90°, centigrade, for a long period of
time, then cooling and precipitating the iron
derivative of albumen by tartaric acid to re-
move noxious salts, substantially as set forth.

11. The process of obtaining an iron com-
120 pound capable of resorption in the mentioned
proportion in the animal organism, which
consists in adding successively to a solution
of an albumen, a solution of tartrate of iron,
a neutral solution of tartrate of sodium and
125 a soda-lye, then warming the resultant solu-
tion to 90°, centigrade, for from two and a half
to four hours, then adding a solution of tartaric
acid to remove the surplus of alkali and then
adding ammonia solution to render the liquid
130 alkaline and finally keeping the mixture at a
temperature of 90°, centigrade, for a period of not
less than twelve hours, then allowing the same to cool,
and then treating it with a solution of tartaric

acid until, it reacts distinctly acid, whereby the iron derivative of albumen is precipitated, substantially as set forth.

12. As a new compound adapted for use as
5 a medicine and an article of food, an iron derivative of albumen containing about ten per cent. of iron and having a dark or light-brown color, which is insoluble in water, but soluble in a strong solution of tartaric acid,
10 and, after being dried, in weakly alkaline cold water, a neutral solution of which will not coagulate on boiling, and an ammoniacal solution of which, in connection with sulfid

of ammonia, reacts in the manner hereinbefore specified.

In testimony whereof we affix our signatures in presence of two witnesses.
